PENNSYLVANIA

DESIGN FOR A SHACKLE LOCK

Application filed May 29, 1930. Serial No. 35,852. Term of patent 7 years.

To all whom it may concern:

Be it known that I, WILSON HEYWARD SMITH, a citizen of the United States, residing at Lancaster, in the county of Lancaster and State of Pennsylvania, have invented and produced a new and original Design for Shackle Locks, of which the following is a specification, reference being had to the accompanying drawings, forming a part thereof.

In said drawings:

Fig. 1 is a front perspective view of a shackle-lock showing my new design; Fig. 2

is a rear view; and Fig. 3 is an end view of the same.

The dominant feature of the invention or design resides in the novel configuration of the casing with well rounded ends or periphery and slightly elliptical or convex sides.

I claim:

The ornamental design for a shackle-lock, substantially as shown and described.

In testimony whereof I have signed my name.

W. HEYWARD SMITH.
